UNITED STATES PATENT OFFICE.

ARNOLD MICHOUUD, OF YVERDON, SWITZERLAND, ASSIGNOR TO CIBLES AUTOMATIQUES MICHOUUD SOCIÉTÉ ANONYME, OF NEUCHATEL, SWITZERLAND, A CORPORATION OF SWITZERLAND.

ELECTRO-AUTOMATIC TARGET.

Application filed January 12, 1924. Serial No. 685,739.

To all whom it may concern:

Be it known that I, ARNOLD MICHOUUD, a citizen of Switzerland, residing at Yverdon, Canton of Vaud, in the Confederation of Switzerland, have invented certain new and useful Improvements in or Relating to Electro-Automatic Targets, of which the following is a specification.

The invention has reference to electro-automatic targets of the type using the shock of the projectile upon the target to control the closing of a circuit actuating an indicator placed within reach of the marksman.

In known targets of this type the surface of the target is subdivided into sectors, segments or independent concentric rings, surrounding a central disc or "bull's eye" and each commanding one or more separate circuit closing members, the result being a complicated and costly construction; and, on the other hand, the target does not afford any precision as to the exact point where the projectile strikes inside the bull's eye.

The target forming the subject matter of the present invention, on the contrary, consists of one single block, made in one with a shaft capable of oscillating under the action of the shock of a projectile round an axis at right angles to the radial plane passing through the axis of the shaft and the point of arrival of the projectile, in such a way as to command the closing of an indication circuit by the agency of at least one pendulum, mounted to oscillate upon the target frame.

The accompanying drawings show by way of example two constructional forms of this target.

Figure 1 is an end view taken behind the target of the first form.

Figure 2 is a lateral elevation thereof.

Figure 3 is a lateral elevation of the second form and

Figure 4 is a diagram showing how eight indications of direction can be obtained in the two forms by means of four pendulums.

The target *a* in the first of these forms has no division and is formed by a metal disc of relatively small diameter, but the thickness of which must be sufficient to enable it to resist the shocks of the projectiles.

This disc is solidly keyed to the end of a horizontal shaft *b* mounted in flexible bear-

ings *c* and *c*¹ carried by the casing or frame *d* of the target. To this frame there is also attached, immediately above the shaft *b*, a horizontal axis *e*, upon which pendulums *f* are so mounted as to oscillate. Each pendulum *f* carries at its free end a ball *f*¹ that bears freely upon the periphery of the shaft *b* at the end of this latter, opposite the target *a*. The points of contact A, B, C, D of the four balls *f*¹ are arranged diagonally at the ends of two diameters extending at right angles to each other through the axis of the shaft *b* (Figure 4).

The method of operation of the target is as follows:

The shock produced by the impact of a ball, say for example at the point X (Figure 4) will cause the target *a* and the shaft *b* to oscillate conjointly round an axis *x*, *x* at right angles to the radial plane passing through the point X.

This oscillation is rendered possible by the elasticity of the bearing *c*, and its amplitude is limited by the bearing *c*¹ which is also elastic and serves as a shock preventer.

The shock of the ball or bullet is thus transmitted by the medium of the shaft *b* to the ball 3 diametrically opposed in relation to the sector III in which the point X (Figure 4) is located, which then controls the closing of a circuit (not shown) actuating in a known manner a signal corresponding to the sector III in the indicator placed within reach of the marksman.

Figure 4 shows that when the shock of the ball takes place in the intermediate sectors, situated between the sectors I, II, III, IV it is transmitted by the shaft *b* simultaneously to two balls, the effect of which is added or deducted in the manner known so as to control a signal distinct from the two respective signals corresponding to these two balls.

In the second form of construction (Figure 3) the target *a*¹ is a Swiss ordnance target A subdivided into four concentric zones. The shaft *b*¹ has a ball and socket joint *b*² by means of which it can oscillate in a spherical bearing *c*² and a free conical end *b*³, intended to cooperate with four groups I, II, III, IV of pendulums *f* comprising four pendulums each. The sixteen balls *f*¹ of these pendulums are maintained at the same distance from the axis of the shaft *b*¹ by

stays f^2 , in such a manner that the amplitude of the oscillations of this shaft must be smaller to actuate one or two balls f^1 of the group of pendulums II than those of group I, or to actuate those of groups III than those of group IV and so on ad sequitur. In this form the different movable parts of the target are regulated and balanced between them so that a ball reaching the zone 4 of the target may produce an oscillation of the shaft b^1 of such an amplitude that it only actuates the group of balls IV in permanent contact at rest with the said shaft.

If the ball strikes one of the zones 3, 2 or 1 of the target, the corresponding group III, II, or I will come into play, simultaneously with those other groups which lie closer to the shaft b^1 .

It will thus be seen that use is made of the direction of the oscillation of a shaft made in one with the monoblock target so as to determine the direction of the blow, and the amplitude of this oscillation so as to determine the distance of the blow from the centre of the target.

In the two forms the weight of the shaft b must approximately balance that of the target in relation to the bearing c, c^2 , so that the inertia does not intervene in the transmission of the shocks produced by the projectile.

What I claim is:

1. In an electro-automatic target the combination with one single block of a shaft made in one with the block and adapted to oscillate under the action of the shock of a projectile round an axis perpendicular to the radial plane passing through the axis of the shaft and the point of arrival of the projectile and one or more pendulums mounted to oscillate on the target frame, whereby the control of the closing of an indication circuit is controlled.

2. In an electro-automatic target the combination with one single block of a shaft made in one with the block and adapted to oscillate under the action of the shock of a projectile round an axis perpendicular to the radial plane passing through the axis of the shaft and the point of arrival of the projectile and one or more pendulums mounted to oscillate on the target frame, whereby the control of the closing of an indication circuit is controlled and means for utilizing the direction of the oscillation of the shaft in order to determine the direction of the blow or impact and the amplitude of this oscillation to determine the distance of the blow from the centre of the target.

3. In an electro-automatic target the combination with one single block of a shaft made in one with the block, enrolled in an elastic bearing, which is carried by the frame of the target, and adapted to oscil-

late under the action of the shock of a projectile round an axis perpendicular to the radial plane passing through the axis of the shaft and the point of arrival of the projectile and one or more pendulums mounted to oscillate on the target frame, whereby the control of the closing of an indication circuit is controlled.

4. In an electro-automatic target the combination with one single block of a shaft made in one with the block having a ball and socket joint, which co-operates with a spherical bearing carried by the frame of the target, said shaft being adapted to oscillate under the action of the shock of a projectile round an axis perpendicular to the radial plane passing through the axis of the shaft and the point of arrival of the projectile and one or more pendulums mounted to oscillate on the target frame, whereby the control of the closing of an indication circuit is controlled.

5. In an electro-automatic target the combination with one single block of a shaft made in one with the block enrolled in an elastic bearing, which is carried by the frame of the target and adapted to oscillate under the action of the shock of a projectile round an axis perpendicular to the radial plane passing through the axis of the shaft and the point of arrival of the projectile and one or more pendulums mounted to oscillate on the target frame, whereby the control of the closing of an indication circuit is controlled.

6. In an electro-automatic target of relatively small diameter the combination with a single block of a shaft made in one with the block and adapted to oscillate under the action of the shock of a projectile round an axis perpendicular to the radial plane passing through the axis of the shaft and the point of arrival of the projectile, said shaft being cylindrical at its free end and co-operating with four balls carried by pendulums mounted to oscillate on the target frame, whereby the control of the closing of indication circuits is controlled, said balls bearing freely upon the periphery of the shaft on four diagonal points arranged at the ends of two diameters drawn at right angles to each other through the axis of the shaft, whereby eight directly different indications are given.

7. In an electro-automatic target the combination with a single block of a shaft made in one with the block and adapted to oscillate under the action of the shock of a projectile round an axis perpendicular to the radial plane passing through the axis of the

shaft and the point of arrival of the projectile, said shaft being conical at its free end and co-operating with four groups of four balls carried by pendulums mounted to oscillate on the target frame, whereby the control of the closing of indication circuits is controlled, said balls being arranged at a uniform distance from the axis of the

shaft, whereby thirty-two different indications are given.

In testimony whereof I have affixed my signature in presence of two witnesses.

ARNOLD MICHOUUD.
